UNITED STATES PATENT OFFICE.

ALEXANDER S. DIMITROFF, OF GLASGOW, MONTANA.

RAIL-JOINT.

1,215,499.

Specification of Letters Patent. Patented Feb. 13, 1917.

Application filed September 5, 1916. Serial No. 118,460.

To all whom it may concern:

Be it known that I, ALEXANDER S. DIMITROFF, a citizen of the United States, residing at Glasgow, in the county of Valley and State of Montana, have invented new and useful Improvements in Rail-Joints, of which the following is a specification.

This invention relates to a new and useful improvement in rail joints and more particularly to a joint of the character adapted to eliminate the customary jar that is caused by the wheels of the car passing over the joints of rails, such as are now used in the construction of railroads throughout the country.

An object of this invention is the provision of a rail joint which eliminates the use of individual fish plates as this rail joint has provided a means integral therewith on opposite sides thereof which may be termed integral fish plates, as they are provided for the same purpose, thus eliminating the use of the customary removable fish plates now in every day use.

Another object of this invention is the provision of a rail having integral fish plates provided thereon to coöperate in producing a substantial rail joint, which may be reinforced by a suitable bed plate adapted to be spiked to a plurality of ties, thus providing a means for substantially preventing the spreading of the rails through the medium of a series of side guards carried by said bed plate and in engagement with the rail on opposite sides thereof. Therefore should the bolts that pass through the integral fish plates binding said rails, break or become loose the bed plate engaging the rails substantially in two places on opposite sides thereof, namely, in close proximity with the points where the reduced ends of the rails engage the larger ends of each other, will prevent the joint from spreading, as clearly illustrated by Figure 1 of the accompanying drawing.

With the above and other objects in view this invention resides in the novel features of construction, formations, combinations and arrangements of parts to be hereinafter more fully described, claimed, and illustrated by the accompanying drawings in which:

Fig. 1 is a top plan view of my improved rail joint,

Fig. 2 is a side elevation of the same, 55
Fig. 3 is an end view thereof,

Fig. 4 is a transverse sectional view taken on the line 4—4 of Fig. 1 looking in the direction of the arrows.

Fig. 5 is a perspective view of the two sections of my rail, separated and removed from the bed plate, and,

Fig. 6 is a similar view of the bed plate removed.

Referring to the accompanying drawings 65 by similar characters of reference throughout the numeral 10 designates in general my improved rail joint which comprises two rails 11 each of which having one end thereof, reduced in formation so as to produce a wedge shaped end 12 thereon, the outer terminal of which is rounded as designated by the numeral 13 while the inner terminal is rounded to form a curved seat designated by the numeral 14 to correspond with the curvature of the rounded end of the outer terminal designated by the numeral 13.

This formation of one end of each rail is continuous throughout the entire height of said rail as clearly illustrated by Fig. 5 of 80 the accompanying drawings, thus it will be observed that when the two wedge shaped ends 12 are brought together the rounded outer terminals 13 of each rail, seat themselves into engagement with the curved seat 75 14, of the other rail, thus making a longitudinally and diagonally disposed joint as clearly illustrated by Fig. 1 of the accompanying drawings.

Each of these sections of rails 11 has 90 formed integral therewith an enlargement 15 which is longitudinally disposed thereon intermediate the head 16 of each section of one rail 11 and the lange 17 thereof, while on the opposite side to said enlargement 15 95 is a lip flange 18 of a corresponding height to that of the enlargement 15 and which is provided to coöperate with each extension 15 so as to produce a neat and substantial terminal at that end of said enlargement to 100 correspond to that at the opposite end thereof, while formed in said enlargements 15, at suitable intervals are a series of apertures 19 which extend horizontally through the entire thickness of each enlargement 15 and 105 sections of rail 11, thus providing a means whereby suitable bolts 20 may be passed through both sections of rails 11 to bind said

sections 11 substantially together through the coöperation of suitable nuts 21 with said bolts 20.

In view of the above it is to be understood that these sections of rails 11 as above set forth could be readily spiked in the customary manner to the ties, after the bolts 20 and nuts 21 are applied, should it seem advisable, as the enlargements 15 provide integral fish plates which eliminate the use of the customary removable fish plate or angle iron now in use, but to provide an absolutely safe and more substantial joint, I have provided this joint as above-described, 15 with a reinforcing means comprising a bed plate 22 which is of sufficient length to bridge two ties, spaced as is customary in railroad construction and illustrated by dotted lines and designated by the letter A 20 upon the accompanying drawings.

Referring more particularly to Figs. 5 and 6 of the accompanying drawings, it will be readily observed that after the sections of rails 11 have been assembled or before, this 25 being left entirely to the discretion of the assembler of such joints, the bed plate 22 is slid beneath the assembled sections of rails 11 until the flange 17 of said rails is passed beneath a plurality of rail guards 23 formed 30 integral with said bed plate and at one side thereof, after which the longitudinal movement of said rails upon said bed plate 22 is limited by a locking member 24 formed integral and intermediate the length of each 35 of said enlargements 15 and which is seated intermediate said rail guards 23 as more clearly illustrated by Fig. 1 of the accompanying drawings.

The opposite side of said bed plate 22 is 40 provided with a plurality of guide rails 25 and after said assembled rails 11 have been properly adjusted to the bed plate as described by the above paragraph a plurality of movable rail guards 26 having grooves 27 45 formed longitudinally therein to correspond with the curvature of the guide rails 25 are moved into engagement with said guide rails 25 and through the coöperation of said guide rails 25 with the grooves 27 formed in each 50 of said rail guards 26, each of said rail guards 26 is moved inwardly along said guide rails 25 until their inward movement is limited by a stop block 28 carried by each 55 of said movable rail guards 26 at their outer end thereof.

In view of the above and by referring to Fig. 6 of the drawings it will be clearly observed that after said movable rail guards 26 have been moved their limit inwardly and 60 along the guide rails 25 the same will then be substantially in alinement with the integral rail guards 23 carried by the said bed plate 22 at the opposite side thereof, whereupon suitable spikes as indicated by dotted

lines and designated by the letter B upon the drawings, may be driven into the customary ties designated by the letter A, thus substantially securing said bed plate 22 to the ties A, by means of the engagement of said spikes B with a suitable plurality of recesses 70 29 formed in each of said plurality of rail guards 23 and 26.

The greatest of stress should be laid upon the fact that by the construction and formation of this joint together with said bed plate 22, I have provided a means that will prevent the sections of rails 11 from spreading should a bolt or two come loose, in fact, should every bolt binding said rails become loose the bed plate 22 will prevent undesired 80 lateral movement of said rails as well as the undesired longitudinal movement of the same, the latter movement being limited as before stated through the medium of locking members 24 formed integral with each of said 85 enlargements 15 which seat themselves intermediate said plurality of rail guards 23 and 26.

It is now thought that the above description together with the accompanying drawings sufficiently sets forth the construction and operation in the assembling of my rail joint to enable those familiar with the art to readily understand the construction and operation in the assembling of the same as 95 well as the many advantages of this device. It should be understood however in this connection that various minor changes in the details of construction may be resorted to within the scope of the appended claims 100 100 without departing from or sacrificing any of the advantages of this invention.

It should also be further understood that I have provided a rail joint adapted for use that will eliminate the customary jar that is 105 caused by the wheels of the car passing over the joints of the rails such as are now in use and that I have provided a rail joint that will fulfil all of the necessary requirements 110 of such a device.

Having thus fully described this invention what I claim as new and desire to protect by Letters Patent is:—

1. A rail joint comprising two rails, each of said rails having a fish plate formed integral therewith and having a series of apertures formed therein for the reception of a series of bolts adapted to bind said rails substantially together, and an extension formed intermediate the length of each of said fish plates and integral therewith, as a means for preventing the undesired longitudinal movement of said rails.

2. A rail joint comprising two rails, each of said rails having a wedge shaped end formed thereon, a series of bolts adapted to bind said rails together, a reinforcing member supporting said rails, a rail guard

formed integral with said reinforcing member at one end thereof, a second rail guard formed integral therewith at the opposite end thereof, a plurality of rail guards movable longitudinally at the opposite side of said reinforcing member as a means whereby each of the same is brought into transverse alinement with one of the said integral rail guards at opposite ends of the said reinforcing member to engage in transverse alinement said rails in close proximity to the wedge shaped ends thereof and means provided for substantially securing said reinforcing member to a plurality of ties 15 through the coöperation of said rail guards with the last mentioned means.

3. A rail joint comprising two rails, a plate supporting the same, a plurality of rail guards formed integral therewith, a means formed integral with said plate to permit a second plurality of rail guards to be moved thereon and a means provided by each of said rail guards for the reception of fastening members to substantially hold said plate in position.

4. A rail joint comprising two rails, a plate supporting the same, a plurality of rail guards formed integral therewith, a plurality of guide rails formed integral with said plate to permit the movement thereon of a second plurality of rail guards, a means provided upon each of the last mentioned rail guards to limit the movement of the same, and a means provided by each of the first mentioned and last mentioned rail guards for the reception of fastening members to substantially hold said plate in position.

5. A rail joint comprising two rails, a reinforcing member supporting the same, a plurality of spaced rail guards formed integral with said reinforcing member at one side thereof, a second plurality of rail guards adapted to be moved longitudinally upon said reinforcing member at the opposite side thereof until in transverse alinement with said integral rail guards to produce a means for substantially engaging said rails at the opposite ends of said reinforcing member and each of said rail guards having a series of recesses formed therein as a means whereby said reinforcing member may be substantially held in position.

6. A rail joint comprising two rails, each of said rails having a fish plate formed integral therewith, a reinforcing member supporting said rails, means carried by said reinforcing member for preventing the undesired lateral separation of said rails and a locking member carried by each of said rails and coöoperating intermediate each plurality of the said longitudinally disposed means to prevent the undesired longitudinal separation of said rails and means for co-

operating with each plurality of the horizontally disposed first-mentioned means for the purpose of substantially securing the reinforcing member to a plurality of ties.

7. A rail joint comprising two rails, each of said rails having a fish plate formed integral therewith, an enlargement formed integral with each of said fish plates, a reinforcing member supporting said rails, a plurality of rail guards formed integral therewith, a second plurality of rail guards movable upon said reinforcing member, each of said plurality of rail guards engaging at one end thereof the integral enlargement of the fish plate, their opposite ends thereof engaging extensions on the said two rails as a means for limiting the undesired longitudinal movement of said rails and each plurality of rail guards arranged on opposite sides of said rails as a means for preventing the undesired transverse movement of said rails and each of said rail guards having a plurality of recesses formed therein for the reception of a plurality of securing members for the purpose of holding substantially the reinforcing member in position.

8. A rail joint comprising two rails, a plate supporting the same, a plurality of rail guards formed integral therewith at one side thereof, a plurality of guide rails formed integral with said plate at the opposite side thereof, a plurality of rail guards each having a groove formed therein for engagement with each of the said guide rails as a means for permitting the movement of said rail guards thereon, a stop member carried by each of the said movable rail guards as a means for limiting the movement of the same and a means provided by the integral rail guards and the movable rail guards for the reception of fastening members to substantially hold said plate in position.

9. A rail reinforcing member comprising a plate having a plurality of rail guards formed integral therewith adapted to overlap the flange of a rail, a plurality of movable rail guards mounted thereon and means provided by each of said rail guards for the reception of fastening members to substantially hold said plate in position.

10. A rail reinforcing member comprising a plate having a plurality of rail guards formed integral therewith at one side thereof, a second plurality of rail guards adapted to be moved longitudinally toward each other upon the opposite side of said plate and means provided by each of said rail guards for the reception of fastening members to substantially hold said plate in position.

11. A rail reinforcing member comprising a plate having a plurality of rail guards formed integral therewith at one side, there-

of, a plurality of guide rails formed integral therewith at the opposite side thereof, a second plurality of rail guards movable upon said guide rails and means provided by each of said rail guards for the reception of fastening members to substantially hold said plate in position.

12. A rail reinforcing member comprising a plate having a plurality of rail guards formed integral therewith at one side thereof, a plurality of guide rails formed integral therewith at the opposite side thereof, a second plurality of rail guards movable upon said guide rails, a stop block carried by each of the last mentioned rail guards to limit their movement upon said guide rails, and means provided by each of said rail guards for the reception of fastening members to substantially hold said plate in position.

13. A rail reinforcing member comprising a plate having a plurality of rail guards formed integral therewith at one side thereof, a plurality of guide rails formed integral therewith at the opposite side thereof, a second plurality of rail guards each having a longitudinally disposed groove formed therein for engagement with said guide rails for the purpose of permitting the movement of said last mentioned rail guards thereon, a stop block carried by each of the last mentioned rail guards to limit their movement upon said guide rails and means provided by each of said rail guards for the reception of fastening members to substantially hold said plate in position.
